UNITED STATES PATENT OFFICE

FRANCIS O. HELTZEL, OF YOUNGSTOWN, OHIO

HIGHWAY MARKER

Application filed September 18, 1932. Serial No. 632,888.

The invention relates to highway or traffic markers for use on pavements of roads, streets and the like where it is intended to mark for zoning purposes such as street crossings, safety zones or traffic lanes and the like.

An object of the invention is to provide a marker having a slightly convex surface provided with a plurality of grooves to prevent the skidding of automobiles which may pass over the same; the grooves all extending from the central or higher portion of the marker to the peripheral or lower portion thereof so as to drain all moisture from the surface of the marker.

Another object is to provide a substantial bearing surface, both at the central portion and peripheral portion of the marker, upon the pavement to which it is applied so as to prevent distortion or flattening of the marker under the weight of heavy trucks, busses or other vehicles.

A still further object of the improvement is to provide a novel spike or pin for fastening the improved marker to the pavement.

The above together with other objects may be attained by constructing the improved marker in the manner described in the following specification and illustrated in the accompanying drawing, in which

Figure 1 is a top plan view of the improved marker showing the grooves thereon in the form of a five pointed star;

Fig. 2, a similar view showing the grooves forming a four pointed star;

Fig. 3, a view similar to Figs. 1 and 2 showing the configuration of an eight pointed star;

Fig. 4, a vertical section through one of the improved markers showing the same spiked in position on a pavement;

Fig. 5, a fragmentary sectional view as on the line 5-5 of Figs. 1, 2 or 3;

Fig. 6, a transverse sectional view of the lower portion of the spike taken as on the line 6-6, Fig. 4;

Fig. 7, a side elevation of a modified form of spike or pin; and

Fig. 8, a similar view of a further modification thereof.

Similar numerals refer to similar parts throughout the drawing.

The improved marker may comprise a sheet metal disk 10 which is slightly convex as best shown in Fig. 4 and provided with the central depressed portion or pocket 11 to receive the head of the spike or pin as will be later described.

The bottom wall of this pocket may be provided with a cross-shaped opening 12 to receive the improved spike, forming a part of the invention, which may be of either cross shape or flat in cross section, as will be later described in detail.

The peripheral portion of the disk is preferably flattened out as shown at 13 in order to provide a bearing surface upon the pavement indicated at 14 in Fig. 4.

In order to strengthen the marker so as to prevent distortion of the same by vehicles passing thereover, as well as to provide a nonskid surface upon the same, and also to provide for drainage of all moisture from the central or higher portion of the marker to the periphery thereof, a plurality of straight grooves 15 are formed in the upper surface of the marker disk leading from the center higher portion of the disk outward and downward to the flat peripheral rim portion 13, the outer ends of said grooves being flush with said flat peripheral portion, as indicated at 16. These grooves may be formed in the marker by stamping or pressing as shown in Fig. 5, producing the reinforcing ribs 17 upon the underside of the marker disk.

In order to provide for the drainage of all moisture outward and downward from the central higher portion of the disk, the inner ends of adjacent grooves should communicate as indicated at 18 and the invention is preferably carried out by so arranging the grooves as to produce a star-shaped configuration which may be in the form of a five pointed star as shown in Fig. 1, a four pointed star as shown in Fig. 2, an eight pointed star as shown in Fig. 3 or a star shape of any other arrangement which may be desired.

In placing the marker disk upon a pave-

ment it will be seen, as shown in Fig. 4, that the peripheral rim portion 13 will have a bearing surface upon the pavement while the central raised portion of the disk will 5 be spaced slightly above the pavement. In order to provide a substantial bearing surface for the central portion of the disk, a washer 19, as shown in Fig. 4, may be provided resting flat upon the pavement and 10 forming a bearing surface for the central pocket portion 11 of the disk and also for the inner communicating ends of the reinforcing ribs 17, thus providing a substantial bearing surface for the greater portion of 15 the marker disk and preventing flattening or distortion of the same by weight of heavy vehicles passing thereover.

The improved spike forming a part of the invention is preferably of cross shape in 20 cross section so as to fit within the cross-shaped opening 12 in the central pocket 11 of the disk and to prevent rotation of the disk. The spike is indicated generally at 20 and the head 21 thereof may be slightly 25 tapered or flared as at 22 to snugly fit within the central depression or pocket 11 of the marker disk, the top of the head being slightly convexed as at 23 to conform to the contour of the upper surface of the disk.

30 Staggered V-shaped notches 24 may be formed in the edges of the wings of the cross-shaped spike or pin or if desired, these notches may be of X shape as shown at 24a in Fig. 7. These notches are for the purpose of permitting the paving material, indicated generally at 25, to creep into the same, in order to hold the spike firmly in place when driven into the paving material, as shown in Fig. 4.

40 The lower end of the spike is provided with a driving and guiding point, each of the wings being beveled at an acute angle as indicated at 26 so as to tend to force the paving material which is displaced inward 45 to snugly engage the inner angles 27 between the wings of the spike.

Instead of making the spike of cross shape, the same may be flat as shown in Fig. 8, this form being especially desirable where it is 50 necessary to drive the spike into a narrow breaker strip of asphalt or the like located in a concrete or cement pavement, the thickness of the spike being just sufficient to permit it to be driven into the asphalt breaker 55 strip between the adjacent concrete surfaces.

This flat spike is relatively thin in cross section, being of the same thickness as the arms or blades of the cross-shaped spike 60 and is very well adapted for driving into the narrow premolded or poured joints of asphalt or tar which are used in some pavements of cement and the like, the flat spike being of substantially the same thickness as 65 the premolded or poured joint.

I claim:

1. A marker having a convex upper surface and a plurality of angular grooves in said upper surface leading from the central higher portion to the outer edge of the 70 marker, said grooves forming a star shape upon the surface of the marker.

2. A marker having a convex upper surface and a plurality of angular grooves in said upper surface leading from the central higher portion to the outer edge of the 75 marker, said grooves forming a five pointed star shape upon the surface of the marker.

3. A marker having a convex upper surface and a plurality of angular grooves in said upper surface leading from the central higher portion to the outer edge of the 80 marker, said grooves forming a four pointed star shape upon the surface of the marker.

4. A marker having a convex upper surface and a plurality of angular grooves in said upper surface leading from the central higher portion to the outer edge of the 85 marker, said grooves forming an eight pointed star shape upon the surface of the 90 marker.

5. A marker having a convex upper surface and a plurality of angular grooves in said upper surface leading from the central higher portion to the outer edge of the 95 marker, said grooves forming a star shape upon the surface of the marker, the outer ends of said grooves being flush with the outer edge portion of the marker.

6. A marker formed from a single sheet 100 of metal of convex shape having a plurality of angular grooves in its upper surface and corresponding ribs in its under surface, the inner ends of adjacent grooves communicating with each other, the outer edge portion of the marker being adapted 105 to bear upon a pavement, and a washer bearing upon the pavement and supporting the central portion of the marker including the inner end portions of said ribs.

In testimony that I claim the above, I have hereunto subscribed my name.

FRANCIS O. HELTZEL.
